DES. 115

4-10-1847

George P. Bowes Esq. of Poughkeepsie, N.Y.
Proprietor of a Patent
Side Plates of a Parlor Guard Cabinet Stove.

Fig. 1. Patented April 10th 1847

115

Def. 115

George P. Bowers Roxbury, & Joseph Pratt Boston, Mass.
Letter Patent (Design No. 115) dated 10th April 1847

The Schedule referred to in this Letter Patent are making
part of the same.

To all Persons to whom these Presents shall come, Be it known,
that we George P. Bowers, of Roxbury in the County of Suffolk
and State of Massachusetts, and Joseph Pratt, of Boston, in the
County of Suffolk and State aforesaid have invented or produced
a new design for the front plate and side plates of the com-
mon square working stone, and have the following description
taken in connection with the accompanying drawings hereinafter
referred to forms a full and exact specification of the same,

The figures of the accompanying plate of drawings
represent our new design. Fig. 1 is an elevation of the front plate
with its ornaments and fig. 2 is an elevation of one of the side
plates with the doors on the same and their ornaments, the
other side plate being precisely similar to this, and the back plate
being plain. Figures. 3, 4, 5, 6, are detail sections on the lines
a-b, c-d, e-f & g-h. (fig. 1) respectively showing the contour of the
important moldings as will be explained in the sequel.

2.

Pl. 11.

On the front plate fig. 1. are three square panels $1. m. n$ surrounded by gothic arches $2. m. n - P P P - 999$ the mouldings of the vertical part of the arches being as shown in section in fig. 3. while that of the curved part is as shown in fig. 4. On each side of this front plate is a pilaster $x x x x$ having the curved mouldings shown in fig. 6. The three panels $1. m. n$ with their arches are precisely similar to each other, as are also the two pilasters, above referred to, and the face of each of said panels has all over it a kind of sunken or indented lace or lattice work as shown partially at the top of the panel in fig. 1. Said lace work being formed by hastening common lace upon the patterns in these places, which occurs the above described result perfectly.

The side plate fig. 2. has three doors arranged on it viz. the oven door $A A A A$ with its small rectangular appendage or projection $B B$; the fire chamber door $C C$; and the ash-chamber door $D D$.

The first-named door $A A A A$ has the panels E, E, E , and the rectangular portion one panel FF , all surrounded by gothic mouldings precisely similar to those above described and denoted at $1. m. n - 2. m. n - P P P - 999$ fig. 1. and having the lace work represented on the panel FF .

The door CC and the door DD , have each of them two panels denoted at FF and GG respectively and arranged and ornamented in every particular like those before described.

On the side plate fig. 2. there are also two pilasters tt , and uu , one at each end of the same, substantially similar as to mouldings &c to those before described and represented at $1. m. n - 2. m. n$ fig. 1.

Having thus described our main door ... st. 11.

Dec. 17. 1855

3

Sealed to us, by Letters Patent, is, the peculiarly ornamented panels hereinbefore specified on the front-plate of the stove, and the several doors of the side-plate, the ornaments consisting of the lace-work on the face of the panels in combination with the gothic moldings or arches round the same as hereinabove set forth, and as represented in the drawings, also, also the combination of said panels on each plate with the pilasters on the same, the whole forming a new design, for the front-plate and side-plates of a common square cooking stove.

In testimony that the foregoing is a true description of our said invention or production we have here set our signatures this twenty fifth day of December in the year eighteen hundred and forty seven
